HANDLE FOR LAUNCHING AN AERIAL TOY OR THE LIKE

Helmut Karl Bross, Weichselgartenstr., Altenberg über Nurnberg 40, Germany, assignor of fifty percent to Frank T. Johmann, Berkeley Heights, N.J.

Original design application Apr. 30, 1963, Ser. No. 74,673.
Divided and this application Sept. 11, 1963, Ser. No. 76,555

Term of patent 14 years

(Cl. D34—15)

FIGURE 1 is a front elevational view of a handle for launching an aerial toy or the like, showing my new design with an aerial projectile shown thereon for illustrative purposes only.

FIGURE 2 is a side view of the handle looking at the left side of FIGURE 1.

FIGURE 3 is a side view of the handle looking at the right side of FIGURE 1.

FIGURE 4 is a top view of the handle.

FIGURE 5 is a rear view of the handle.

FIGURE 6 is a sectional view taken along the lines 6—6 of FIGURE 5 to illustrate the contour of the handle.

FIGURE 7 is a sectional view taken along the lines 7—7 of FIGURE 1 to illustrate the contour of the handle.

This application is a division of my co-pending application D. 74,673 filed April 30, 1963.

I claim:

The ornamental design for a handle for launching an aerial toy, or the like, as shown and described.
